UNITED STATES PATENT OFFICE.

CHARLES J. EICHHORN, OF NEWARK, NEW JERSEY, ASSIGNOR TO THE TEA TRAY COMPANY OF NEWARK, N. J., A CORPORATION OF NEW JERSEY.

ELECTRIC-LIGHT HOOD.

No. 861,445.

Specification of Letters Patent.

Patented July 30, 1907.

Application filed July 25, 1906. Serial No. 327,640.

To all whom it may concern:

Be it known that I, CHARLES J. EICHHORN, a citizen of the United States, residing in Newark, county of Essex, and State of New Jersey, have invented certain 5 new and useful Improvements in Electric-Light Hoods, of which the following is a specification.

The objects of the invention are to provide an improved means for supporting the shade or attaching it to the bracket or arm from which it is suspended; to 10 enable such attachment to be more firm and rigid, and to facilitate and lessen the labor of mounting the hood in position for use; to provide for this purpose a central bushing for the shade or hood; to provide a simple and inexpensive construction, and to obtain other advantages and results as may be brought out in the following 15 description.

Referring to the accompanying drawings, in which like numerals of reference indicate corresponding parts in each of the several figures, Figure 1 is a central sectional view of an electric lamp provided with a hood of my improved construction; Fig. 2 is a similar section on larger scale of the bushing in which my invention more particularly inheres; Fig. 3 is a plan of said bushing and portion of the hood shown in Fig. 2, and Fig. 20 25 4 is a view of the same from beneath; Fig. 5 shows the bushing detached from the hood and having its parts separated; Fig. 6 shows a portion of the hood-body adapted to receive the bushing; and Fig. 7 is a view of the same from the under side of the hood with the 30 top part of the bushing inserted.

In said drawings 1 indicates the upper or top part of a hood of any ordinary construction in general, having a lower part 2, connected thereto by catches 3, so as to be removable. These parts 1 and 2, it will be understood, are of sheet metal, the lower one being enameled white or otherwise prepared in any suitable manner to serve as a reflector, and the upper portion 1 being japanned or otherwise finished as is common in the art. In the said upper portion 1 of the hood, I form a central 35 opening or aperture 4, which is preferably circular with the exception of two opposite sides being filled in to the chords of short arcs of the circumference, as at 5, referring more particularly to Fig. 6 of the drawings. In this aperture 4, is inserted the bushing 6, 40 45 which is a part of my invention and which comprises upper and lower, or male and female, parts 6 and 7 respectively. The upper one, 6, of these parts comprises a shank which is threaded exteriorly as at 9, and a flange 10 radially projecting from the top of the shank 8. Said shank is furthermore flattened at portions of its outer threaded surface, as at 11, 11 said flattened portions corresponding to the flattened portions 5 of the aperture in the hood. Said shank 8 is thus adapted to be inserted in the said opening or aperture 4 and fit

the same without any possibility of being turned 55 therein, while the flange 10 lies upon the upper surface of the hood portion 1, around the said aperture 4 therein.

The lower portion 7 of the bushing comprises merely a nut adapted to be screwed upon the projecting shank 8 at the inner or under side of the hood, said 60 part 7 for this purpose being interiorly threaded and exteriorly providing an angular wrench receiving surface 12. It will be understood that in assembling the hood, the said parts of the bushing are screwed firmly together, clamping the hood portion 1 firmly between 65 themselves, as clearly shown in the drawings.

The shank 8 of the bushing is interiorly bored out and threaded as at 13, and in assembling the parts of a lamp, receives a nipple 14, which usually comprises a piece of tubing threaded on its outer surface, as 70 shown in drawings. This nipple when screwed into place is long enough to project considerably above and below the bushing, and at its lower end receives the socket 15 for a lamp 16, the wires 17 from said socket extending up through the tubular nipple. The 75 upper or outer threaded end of the nipple 13 receives a coupling 18, and thus connection is enabled to be made to the threaded end 19, of a tubular arm, bracket or other supporting means, and through which the wires 17, are continued.

My improved construction secures a very strong and effective connection of parts and is simple and inexpensive so that it can be readily applied and widely used. Furthermore the invention enables the hood and bushings to turn as a unit, so that in screwing the 80 parts together in setting up a lamp, it is necessary only to turn upon the outer edges of the hood or shade to turn the said bushing and thus great convenience is secured as well as increased power from the leverage or larger radius of the hood.

This device is of particular utility by reason of the fact that its parts are adjustable, and especially so as they are adjustable by hand so that the workman may leave the shop with the parts and put them in place at the point of use without employing any tools. That is to say, he would first screw the coupling 18 onto the support 19 (if the latter did not already have an exteriorly threaded end like the threads within the coupling), and he would then adjust the nipple 14 through the bushing so that its upper end would project sufficiently, then adjust the socket 15 on the lower end of the nipple so that the lamp would project the proper distance from the hood, then screw the upper end of the nipple into the coupling until the bushing struck the lower end of the coupling, and finally by grasping the periphery of the hood itself he could turn it and the bushing and nipple so as to grind the bushing against the lower end of the coupling and cause it to

serve as a jam nut to prevent the nipple from unscrewing from the bushing. Throughout these steps if the threads are properly proportioned no tools are necessary; and as the only force required is in the last 5 step, the fact that the workman can use the larger diameter of the hood as a lever with which to grind the bushing against the coupling gives him the advantage of the use of a tool without the disadvantage of having to carry it. The wires which project through the 10 port and nipple are later connected with the lamp, in a manner which will be understood.

Having thus described the invention, what I claim as new is:

1. In an electric light hood, the combination with a 15 sheet metal body portion having an aperture therein which is circular with the exception of a flattened chordal portion, of a bushing comprising a male portion having an exteriorly threaded shank seated in said aperture and shaped to fit the same, and a female portion adapted to be 20 screwed upon said shank to grip the edges of the body portion of the hood around said aperture, said male portion being internally threaded throughout its length, and an exteriorly threaded nipple adjustable through the male portion and adapted to connect with the support at its 25 upper end and the socket at its lower end.
2. In an electric light hood, the combination with a sheet metal body portion having an aperture therein, of a bushing comprising members one of which has an exteriorly threaded shank inserted in said aperture and a 30 flange engaging the hood, said shank and aperture being shaped and fitted to prevent relative rotation of the bushing and hood, the other member being adapted to screw on to the said shank and clamp the body portion of the hood between itself and the flange of the first member, an 35 exteriorly threaded nipple screwed completely through said

first-mentioned member and adapted to carry the socket at its lower end, a threaded support, and a coupling connecting the threads of the support with those on the upper end of the nipple, said bushing serving as a jam nut for the coupling.

40

3. In an electric light hood, the combination with a sheet metal body portion having an aperture therein, of a bushing comprising members one of which has an exteriorly threaded shank inserted in said aperture and a flange engaging the hood, said shank and aperture being 45 shaped and fitted to prevent relative rotation of the bushing and hood, the other member being adapted to screw onto the said shank and said shank being interiorly threaded, a supporting nipple screwed into said shank and projecting at both ends beyond the said bushing, a socket adjustably screwed onto the lower end of the nipple, a coupling adjustably screwed onto its upper end and against the bushing which latter serves as a jam nut for the nipple, and a support for the coupling.

50

4. In an electric light hood, the combination with the 55 hood proper having spaced upper and lower parts, both having central openings and that in the former being irregular, a tubular bushing comprising two members of which one has an exteriorly threaded shank shaped to fit said irregular opening and a radial flange to rest upon the 60 upper part and the other screws onto said shank and is adapted to clamp said part against said flange; of an exteriorly threaded nipple adjustable longitudinally through the bore of said coupling, a lamp socket adjustable on its lower end, a support, and a threaded coupling on the latter into which the upper end of said nipple is adjustably screwed and against which the coupling serves as a jam nut.
